ATTORNEY

UNITED STATES PATENT OFFICE

SAMUEL LADLEY, OF SWISSVALE, PENNSYLVANIA, ASSIGNOR TO WESTINGHOUSE ELECTRIC & MANUFACTURING COMPANY, A CORPORATION OF PENNSYLVANIA

INTERNAL-COMBUSTION ENGINE

Application filed April 1, 1922. Serial No. 548,842.

My invention relates to internal-combustion engines and it has particular relation to means for controlling the supply of fuel thereto.

- 5 My invention has for one of its objects to provide an arrangement for automatically controlling the quality and the quantity of the fuel mixture supplied to an internal-combustion engine.
- 10 A second object of my invention is to provide an arrangement of the character indicated above in which the quality and the quantity of the fuel mixture may be simultaneously regulated to maintain substantially 15 constant engine speed.

My invention comprises broadly a governor for automatically controlling butterfly valves located respectively in the fuel-intake and the air-intake pipes of an internal-combustion 20 engine. Under normal operating conditions, both valves are controlled simultaneously in accordance with the speed of the engine. The automatic regulation of the quality and the quantity of the combustible mixture operates 25 to maintain the engine speed substantially constant.

In the accompanying drawing,

Figure 1 is a view, partially in side elevation and partially in section, of an internal-combustion engine embodying my invention.

Fig. 2 is a similar view, in enlarged detail, of a portion of the fuel-controlling means.

Referring particularly to Fig. 1, an internal-combustion engine 1 which may, for example, be employed in connection with isolated power plants, commonly known as farm-lighting plants, comprises a base member 2, a crank case 3 and a cylinder 4. A fuel-intake pipe 5, which is connected in a well-known manner to the cylinder 4, is controlled by a butterfly valve 6 that is commonly known as the "throttle".

The fuel which may be, for example, kerosene or other low-grade hydrocarbon compound, is contained in a tank 7 that is located within the base member 2. The fuel passes through a check valve 8 and a pipe 9 having a bore of relatively small diameter that opens into the throat of a Venturi tube 10 to which the intake pipe 5 is connected. An air-intake

pipe 12, which is connected to the outer end of the Venturi tube 10, is controlled by a butterfly valve 13.

The details of the arrangement whereby a pipe of relatively small bore supplies fuel to the throat portion of the Venturi tube constitutes the subject-matter of the copending application of Newill & Dicksee, Serial No. 548,806, filed April 1, 1922 and assigned to the Westinghouse Electric & Manufacturing Company.

A centrifugal governor 14, which may be of any usual or ordinary construction, is operatively connected to the crank shaft of the engine by means of a shaft 15. The centrifugal governor comprises a plurality of weight members 16 which, when they move outwardly, exert a lever action upon the slideable sleeve member 17, causing the latter to engage a lever 18. The latter is connected to a link 19 that is connected by a lever arm 20 to the butterfly valve 6 and by a link 21 and lever arm 22 to the butterfly valve 13.

Referring particularly to Fig. 2, the valve 13 is mounted on a rotatable shaft 24 that is journaled in the sides of the air-intake pipe 12, the shaft being of such length as to extend beyond the sides of the pipe. The lever arm 22 is rotatably mounted on one of the projecting portions of the shaft 24. A manually-operable lever arm 25, which is rigidly secured to the shaft 24 adjacent to the lever arm 22, is provided with a lug 26 (Fig. 1) that is adapted to engage the lever arm 22. The other projecting portion of the shaft 24 is surrounded by a coil spring 27 that is secured at one end to the shaft and at its other end to the pipe 12.

The spring 27 tends to rotate the shaft 24 and the valve 13 in a clockwise direction, as viewed in Fig. 1 or as viewed from the right in Fig. 2, and thereby maintain the engagement of the lug 26 and the lever arm 22 under normal operating conditions. From the foregoing description, it will be apparent that the valve 13 may be rotated or rocked in a counter-clockwise direction against the force of the spring 27 and relatively to the lever arm 22.

The details of the arrangement whereby the

valve for controlling the air-intake pipe may be controlled manually constitutes the subject-matter of the copending application of C. B. Dicksee, Serial No. 550,371, filed April 7, 1922 and assigned to the Westinghouse Electric & Manufacturing Company.

In starting the engine, it is desirable that a comparatively rich mixture be supplied to the engine cylinder. When the parts are in the respective positions in which they are illustrated in Figs. 1 and 2, the rotation of the engine crank shaft at relatively low speed would not materially affect the position of the valve 13. Accordingly, in order to reduce the quantity of air admitted to the pipe 12 and to correspondingly increase the proportion of fuel in the combustible mixture, the lever 25 is pressed downwardly, that is, rotated in a counter-clockwise direction, by the operator. The engine is then cranked by the usual electric generator 29 operating as a motor, or by other usual or suitable means.

When the engine starts, the lever 25 is released, and the valve 13 is returned by the spring 27 to its position relatively to the lever 22 in which it is illustrated in Figs. 1 and 2. The centrifugal governor automatically and simultaneously controls the valve 6 to regulate the quantity of fuel mixture supplied to the internal-combustion engine and the valve 13 to control the quality or richness of the fuel mixture by varying the proportion of air admitted during the suction strokes of the engine.

From an inspection of Fig. 1, it will be noted that the valves 6 and 13 occupy their respective fully open positions simultaneously. The relative lengths of the lever arms 20 and 22 and their relative angular positions are such that the valve 13 for controlling the air inlet is actuated toward its closed position at a rate which exceeds that of similar movement of the fuel-controlling valve 6. This arrangement is desirable by reason of the fact that the quantity of fuel drawn from the pipe 9 by the air drawn through the Venturi tube across the opening of the pipe 9 varies with the velocity of the air. The velocity diminishes with the closing of the valve 6. The valve 13, however, closes at such increased rate as to increase the vacuum produced by the engine piston to such degree as to compensate for the decrease in air velocity.

It will be appreciated that I have provided a simple and efficient means for automatically controlling the supply of combustible mixture to an internal-combustion engine during normal operation of the engine.

The character and quantity of the fuel mixture is so controlled as to insure substantially constant speed of the engine under varying loads.

I claim as my invention:

1. In an internal-combustion engine, the combination with a fuel-intake pipe and an

air-intake pipe and a valve for controlling each of said pipes, of automatic means for maintaining the speed of said engine substantially constant comprising means for simultaneously controlling said valves whereby they both occupy their fully open positions simultaneously and are actuated toward their respective closed positions at different rates.

2. In an internal-combustion engine, the combination with a fuel-intake pipe and an air-intake pipe and a valve for controlling each of said pipes, of automatic means for maintaining the speed of said engine substantially constant comprising means for simultaneously controlling said valves whereby they both occupy their fully open positions simultaneously and the valve for controlling the air-intake pipe is actuated toward its closed position at a rate greater than that of the other valve.

In testimony whereof, I have hereunto subscribed my name this 24th day of March, 1922.

SAMUEL LADLEY.
